UNITED STATES PATENT OFFICE

168,640

APPLIQUE EMBLEM OR SIMILAR ARTICLE

Charles L. Smith, Athens, Ohio, assignor to Ohio Sesquicentennial Commission, Columbus, Ohio

Application September 13, 1952, Serial No. 21,444

Term of patent 3½ years

(Cl. D3—9)

To all whom it may concern:

Be it known that I, Charles L. Smith, a citizen of the United States of America, and a resident of Athens, in the county of Athens and State of Ohio, have invented a new, original, and ornamental Design for an Applique Emblem or Similar Article, of which the following is the specification, reference being had to the accompanying drawing, forming a part hereof:

The figure is a plan view of an applique emblem or similar article, showing my new design.

I claim:

The ornamental design for an applique emblem or similar article, substantially as shown.
CHARLES L. SMITH.
